THERMAL TIME DELAY

Robert B. Brode, Silver Spring, Md., assignor to
the United States of America as represented by
the Secretary of the Navy

Application September 8, 1943, Serial No. 501,572

1 Claim. (Cl. 102—70)

1

This invention relates to safety devices for projectile fuzes and more specifically to a novel thermal safety delay device for use in fuzes for rotating projectiles.

An object of this invention is to provide a safety delay device for fuzes, which comprises a safety gate normally separating the detonator squib from the usual booster charge and secured in its closed or safe position by a fusible element. A heating charge is ignited in response to the force of setback when the projectile is fired, and after a predetermined length of time, the fusible element becomes melted or sufficiently softened by the heat to permit centrifugal force to move the safety gate to an unarmed position.

A further object of this invention is to provide a thermal safety delay device which will withstand dropping and tumbling, and which will not operate to arm the fuze until acted upon successively by a force of setback and centrifugal force.

A further object of this invention is to provide a thermal safety delay device which is compact, reliable, simple, and adaptable to large scale production.

Other objects and many of the attendant advantages of this invention will be appreciated readily as the same becomes understood by reference to the following detailed description, when considered in connection with the accompanying drawings, wherein:

Fig. 1 is an axial sectional view of one form of the new thermal safety delay device in safe position;

Fig. 2 is a similar view of the device in its armed position; and

Fig. 3 is a fragmentary transverse sectional view taken in plane 3—3 of Fig. 1.

In the drawing, the numeral 10 represents the body of the device. The body is of cylindrical shape and is designed to fit tightly within a projectile casing with the upper end of the body toward the nose of the projectile. An axial passage 11 is formed in the body 10 and extends almost entirely through the body from the bottom thereof. Near the top of the body, a radial opening 12 extends inwardly from the periphery of the body and communicates with the upper end of passage 11. A squib 13 is located at the inner end of opening 12 so as to be positioned at the upper end of passage 11. Wires 14 are provided for operating the squib electrically.

Between the squib and the bottom of the body 10, a cylindrical opening 15 extends into the body from the periphery thereof almost to the passage 11, the opening being provided with a threaded

2

closure member 16 at its outer end. Near the center of the body, the opening 15 narrows to form a reduced portion 17 which intersects the passage 11, the opening 15—17 extending through the major portion of the diameter of the body. At the inner end of opening 15 adjacent the reduced portion 17 is a shoulder 20 which serves to position a pellet 21 in the opening 15, the pellet 21 being made of metal or other suitable heat conducting, noninflammable material. The outer end of pellet 21 is hollowed out at 22 to receive a charge 23 which, when ignited, will heat the pellet. A gate 24 is slidably mounted in opening 17 and is urged inwardly by a spring 25 which bears against the closed end of reduced opening 17. By means of a fusible element 26, the gate 24 is attached to pellet 21 and is thus retained in the position shown in Fig. 1, in which it closes passage 11.

20 Near the periphery of the top of the body 10, a cylindrical passage 27 extends downwardly into the body so as to communicate at its lower end with opening 15 near the outer end thereof. A threaded plug 28 is provided to close the upper end of passage 27. A plunger 29, pointed at its lower end, is slidably mounted in passage 27. A cap holder 30 carrying a firing cap 31 is mounted in opening 15 directly below the point where it communicates with passage 27. A spring 32 bears 25 against the lower end of plunger 29 and tends to prevent contact of the plunger with the firing cap 31.

In operation, the parts of the device are initially in the position shown in Fig. 1 of the drawing, with the gate 24 closing passage 11 which otherwise would provide direct communication between squib 13 and the usual booster charge (not shown). Since the passage 11 is closed by gate 24, the booster cannot be detonated by premature firing of the squib. When the projectile carrying this device is fired from the gun, the force of setback moves plunger 29 downwardly against the pressure of spring 32 until the point of the plunger strikes and fires cap 31 which, in turn, ignites heating charge 23 in pellet 21. After a predetermined time, pellet 21 becomes heated and conducts a sufficient amount of heat to the fusible element 26 to soften or melt the same. When this occurs, gate 24 is free to move outwardly under the action of centrifugal force against the resistance of spring 25, and in so doing opens passage 11, thus arming the fuze. With the gate 24 no longer blocking passage 11, firing of the squib will detonate the booster charge 50 through passage 11.

It will be observed that several features of the device prevent premature opening of the gate 24 to arm the device. Spring 32 prevents contact of the plunger 29 with the cap 31 except when the plunger is acted upon by a very large force of the magnitude of that produced by setback, thus making the device safe against premature arming by accidental dropping which might otherwise prematurely ignite the charge 23. Should the gate 24 become prematurely detached from pellet 21 by accidental breaking of the fusible member 26, the spring 25 is of sufficient strength to hold the gate 24 in its closed position, and the large centrifugal force generated by a rapidly spinning projectile is necessary to move the gate 24 outwardly against spring 25. Thus, the device is safe against premature arming by tumbling. As a result of the incorporation of these safety features, the device will not be armed except when acted upon successively by a force of setback and centrifugal force.

Obviously many modifications and variations of the present invention are possible in the light of the above teachings. It is therefore to be understood that within the scope of the appended claim the invention may be practiced otherwise than as specifically described.

What is claimed is:

In a fuze for a rotating projectile, a substantially cylindrical body having an axial ignition bore, a squib at one end of said bore, said body having a substantially diametrically located passage intersecting said bore and closed at both

ends, a gate member shiftable in said passage, a spring lodged in one end of the passage and urging said gate member into position to close said bore, thereby preventing the transmission of ignition from said squib through said bore, a metallic pellet lodged in the other end of said passage, said pellet having a cavity therein, a heat-producing composition in said cavity, a fusible element connecting the inner end of said gate member to the adjacent end of the pellet, and means actuated by setback to ignite said composition, thereby heating said pellet and melting the fusible element to release the gate member, which thereupon moves radially outward against the spring, under the influence of centrifugal force, to open the ignition bore.
